STRETCH-WRAP FORMING MACHINE

Walter G. Wheeler, Los Angeles, and David C. Kramer, Redondo Beach, Calif., assignors to Richard Seifried, Playa del Rey, Calif.

Application July 26, 1952, Serial No. 301,024

12 Claims. (Cl. 153—32)

1

This invention relates to a machine for forming, by stretching and wrapping, sheets of tapered thickness and of initial rectangular or trapezoidal form.

An object of the present invention is to provide a machine to exert an initial stretch force on a sheet as indicated, to wrap the sheet around a die to a desired angular degree up to a maximum wrapping angle of 180° while the sheet is stretched to its elastic limit, and, finally, subjecting the sheet so wrapped to a final stretch force by applying additional tension thereon to set the sheet against spring-back.

Another object of the invention is to provide a machine that, in applying initial stretch, applies a stretch-leveling force to remove wrinkles, bulges, etc., from commercial sheets so that they are quite flat and level, being stretched flat by such an operation.

A further object of the invention is to provide a machine for the purpose indicated and to employ hydraulic units to control and create the stretching, wrapping and setting forces in said units.

A still further object of the invention is to provide an hydraulic machine of the nature indicated in which plural banks of hydraulically operated mechanisms are provided for exerting different degrees of stretch force on a sheet being stretch-wrapped and to provide means to exert on an intermediate portion of the sheet the average of the forces exerted on the end portions so that the sheet is uniformly stretched, particularly when stretched over a die of conical form.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a top plan view of a stretch-wrap forming machine according to the present invention.

Fig. 2 is a longitudinal sectional view as taken on line 2—2 of Fig. 1.

2

Fig. 2a is an enlarged fragmentary cross-sectional view as taken on line 2a—2a of Fig. 2.

Fig. 3 is a cross-sectional view as taken on line 3—3 of Fig. 1.

Fig. 4 and 5 are enlarged cross-sectional views of details of construction.

Fig. 6 is an edge view of a taper-sectioned sheet adapted to be handled by the present machine.

Fig. 7 is a semi-diagrammatic view of one side of one bank of the present machine, showing control means therefor.

Fig. 8 is a diagrammatic view showing the manner of application of dividing valve means whereby the hydraulic units of the middle of three banks of such units is controlled by the units of the two outer or end banks.

Fig. 9 shows a series of fragmentary detail views of the different positions of control switch means employed in the invention.

The machine embodying the present invention is not limited as to size nor as to the force that may be applied thereby. However, since the stretch forces involved are quite high in order to reach the elastic limit of, for instance, a sheet of aluminum alloy of substantial thickness, said machine, in practice, is quite large and powerful. The drawings show a machine, as at present contemplated, to a greatly reduced scale.

Actually, said machine is about thirty-one feet high with the portions above the pit about ten feet high, and about sixty-six feet across as in Fig. 2. A machine of this size is intended to handle a maximum sheet that is $\frac{5}{8}$ inch thick, twenty feet long, and thirteen feet wide. The sheet is designated 9 in the drawings.

While the machine components may be mounted in a fabricated frame, the same, as shown, are preferably mounted on the concrete lining 10 of a pit 11. The machine that is illustrated comprises, generally, die means 12 fixedly positioned transversely above the pit 11 centrally of its long dimension, sheet-tensioning or -stretching means 13 mounted on the pit lining 10 on opposite sides of the die means, control means 14 carried by each tensioning means, a sheet-gripping jaw 15 carried by each control means, jaw-positioning means 16 to control the position of the jaws 15 and to return them to sheet-gripping position after a wrapping operation, actuating means 17 for wrapping sheet 9 around die means 12 and for imparting a final set to the wrapped sheet, and means 18 to position the actuating means to obtain the most ef-

fective line of pull on the wrapped sheet by the actuating means.

It will be noted that the machine is symmetrical with die means 12 at the middle thereof and that the means 13, 14, 15, 16, 17 and 18, on one side of the die means, are identical to said means on the opposite side. Therefore, the following description of one each of said means will serve to describe the counterpart on the opposite side.

Die means 12 comprises a die support platen 20 fixedly mounted atop a transverse structural member 21 that has its ends embedded in or supported by the opposite walls 22 of concrete lining 10. Die platen 20 mounts a die 23 formed according to the shape to which a sheet 9 is to be bent. The die shown is tapered although the same may be of uniform width as will hereinafter be seen.

Sheet-tensioning means 13 comprises a bracket 24 affixed atop an end wall 25 of lining 10, an hydraulic cylinder 26 having therein a piston 27 provided with a rod or stem 28, and a set of gimbal pivots 29 mounting said cylinder in said bracket. Said pivots 29 comprise a transverse horizontal pivot 30 mounting a ring 31 on bracket 24 and a pivot 32, perpendicular to pivot 30, mounting a collar 33 in ring 31 and affixed to cylinder 26. Pivot 30 is parallel to the longitudinal dimension of die 23. Therefore, cylinder 26 is mounted for pivotal movement in a vertical plane that is transverse to said die. Pivot 32, being perpendicular to pivot 30, mounts said cylinder for movement in the plane of die 23 or in a plane extending at an angle through pivot 30. In other words, cylinder 26 on gimbal pivots 29, has limited universal movement in its mounting bracket 24. This cylinder, as are the other cylinders hereinafter described, is provided with connections to a source of hydraulic fluid to project or retract piston rod 28 as desired. Such connections are not shown because of their conventionality.

The projecting end of piston rod 28 is provided with fork-like fitting 34 that has forwardly directed spaced ears 35 that mount control means 14, and downwardly directed spaced ears 36 that connect to actuating means 17.

Control means 14 comprises an hydraulic cylinder 37 carried by a transverse pivot 38 between ears 35 of fitting 34, a piston 39 in said cylinder, and a piston rod 40 on said piston and extending forwardly from cylinder 37. A clevis 41 is provided on the projecting end of rod 40.

A vertical pivot 42 connects said clevis to sheet-gripping jaw 15 in a manner that allows the latter to assume various angular positions relative to the plane of control means 14.

As shown in Figs. 1 and 3, the components of the machine are provided in plural banks. Three such banks are shown, but the number may be increased or decreased, as desired. However, on each side of die 23 there is provided but one sheet-gripping jaw 15, the same being connected by pivots 42 to the different banks that are provided. Thus, each bank, by independent action, influences the movement of and the force applied to said jaw.

Jaw 15 comprises an elongated bar 43 which is provided in its forward face with a longitudinal slot 44. Within said slot is preferably provided a plurality of grippers 45 which are individually operated to grip sheets 9 of uniform thickness or sheets of tapering thickness. These grippers are not shown in detail because they generally comprise conventional vise jaws that

may be moved together or apart by suitable means, for instance hydraulic cylinder means.

Jaw-positioning means 15 is provided for moving the jaw means 15 to a position receptive of a lateral edge of sheet 9, i. e., to a loading position. Said means comprises an extension of pivot 38, which is affixed to cylinder 37, an arm 46 fixedly mounted on said extension, and an hydraulic cylinder 47 pivotally carried by fitting 34 and having a piston therein that is provided with a piston rod 48 connected to the end of said arm 46. It will be apparent from Fig. 1 that jaw means 15 and control means 14 can be angularly adjusted on pivot 38, relative to the axis of piston rod 28, to direct the sheet-receiving slot 44 as desired.

The actuating means 17 for wrapping the sheet 9 around die 23 comprises an actuating hydraulic cylinder 49 having a piston 50 therein, and a piston rod 51 extending upwardly from said cylinder. The means 17 has a generally vertical disposition in pit 11. An eye 52 extends from the lower end of cylinder 49, and a clevis 53 is provided on the upper end of rod 51. Said clevis and the ears 36 of fitting 34 are connected by a universal knuckle 54 by means of mutually transverse pivots 55 and 56. Eye 52 has a universal gimbal mount that comprises a pivot 57 connecting said eye to a ring 58, and a transverse pivot 59 that connects said ring to opposite slide blocks 60. The latter are mounted in slideways 61 provided in support walls or brackets 62 longitudinally disposed on the bottom of pit 11.

Said latter gimbal mount provides for universal angular disposition of actuating means 17, the knuckle 54 and its pivots 55 and 56 allowing such angular movement with respect to the movements of tensioning means 13.

The means 18 effects the general disposition of means 17 relative to die 23. As shown, said means comprises an hydraulic cylinder 63, mounted on a bracket 64 in the bottom of the pit 11, and provided with a piston 65 from which extends a piston rod 66. The latter, through a connection 67, connects to slide blocks 60. It will be clear that the means 17 is disposed as desired by suitable projection or retraction of rod 66 to slide blocks 60 in their ways 61.

Operation using a parallel-sided die

After a parallel-sided die 23 is formed, the same is placed on and secured to die platen 20. The positioning means 18 on both sides are used to move the pivots 59 of actuating means 17, along slideways 61, so that jaws 15 are directly beneath the opposite edges of the die. This position is shown by the dot-dash lines of Fig. 2. This initial set-up procedure is important because it becomes possible for the final setting pull on a sheet to be applied tangent to the die, thereby eliminating any tendency of the jaws to pull away from the die.

From this initial set-up position, the means 13, 16 and 17 are manipulated to bring the jaws 15 to a horizontal position and into gripping engagement with the opposite lateral edges of a sheet 9 lowered into position on die 23. The three cylinder means are controlled as desired to align the jaws with the top of the die and also move them toward each other to effect engagement of the sheet edges in slots 44. In this manner, the sheet is gripped without tension, as shown by the full-line position of the parts in Fig. 2.

Now, pressure fluid is admitted into the forward ends of cylinders 26 to exert a tension

5

force on sheet 9 until the elastic limit of the material of said sheet is reached. During this application of force by cylinders 26, the control means 14 are employed to insure the correct degree of tension force on the sheet by admitting hydraulic pressure into cylinders 37 to retract pistons 38. Thus, the means 13 is used for approximate application of force and the means 14 for a finer and more controlled application.

With the sheet 9 stretched to its elastic limit to insure that the metal flows smoothly and evenly around the die, the wrapping cycle is started. The actuating means 17 are operated by admitting pressure fluid into the upper ends of cylinders 49 to retract pistons 50 and exert a pull-down force on fittings 34. This application of force causes the means 13 and 14 to change their relative angular position on pivot 38, and both said means to change angular position relative to the means 17 on pivot 55. As the piston rods continue to retract, the gripping jaws 15 are swung in curved paths around the sides of die 23. Since the control means 14 and jaws 15 are free to pivot as above, they at all times remain in the line of pull exerted by means 17.

As the pull-down wrapping force of actuating means 17 is applied, the tensioning means 13 are controlled to pay out or decrease their force. By balancing the decreasing force of means 13 with the increasing force of means 17 a constant force is continuously applied on sheet 9. The control means 14 controls the rate of the decreasing force of means 13.

This action can be stopped at any intermediate stage when the opposite lateral edges of sheet 9 assume angular positions as desired. Such intermediate stage is when the sheet edges define an included angle between 180° and more than 0°. When a zero angle is desired, i. e., when the lateral edges of the sheet are brought into parallelism, the wrapping cycle is continued until means 17 pulls straight down. At this stage, also shown by the dot-dash lines of Fig. 2, all of the pulling force has been transferred from the tensioning means 13 to the actuating means 17.

After the desired amount of wrap has been attained, the actuating means 17 apply an additional general force and the control means 14 apply a control for said force to impart an elongating final setting pull on the sheet. This final stretch minimizes spring-back and, therefore, insures retention of the formed shape of the sheet.

At this time, grippers 45 are released and the formed sheet is removed from the die. Since the actuating means 17 finishes its cycle of operation in the same position it was initially set, it is only necessary to return the jaws 15 to their initial sheet-gripping position for a repetition of the operation on a subsequent sheet, the means 16 being employed to return said jaws to aligned position.

While the foregoing describes a symmetrical wrapping operation with both edges of the sheet wrapped the same amount, it will be evident that only one side of the sheet may be wrapped while the other is held in tension, or one side may be wrapped to a greater angular degree than the other. Needless to say, it is only necessary to maintain equal pulling forces on both sides of the sheet so that the latter does not shift relative to the die.

Operation using a tapered or conical die

In the previously-described operation, the jaws 15 describe a curved path in which any position

6

thereof is parallel to any other position and all positions are parallel to the die. The ability of the machine to form conically shaped or bent sheets depends on the ability of said jaws to rotate, tilt or oscillate in two planes as well as to move parallel to a conical die. In other words, the jaws must be able to oscillate in a horizontal plane and rotate in a vertical plane simultaneously, and such oscillation and rotation must be compounded in any desired proportional degree.

As above stated, the jaws must be free to move in a path always parallel to the slant height of a conical die for the reason that the same has no diameter that is perpendicular to the edge. Otherwise, the sheet will slide over the die during wrapping.

The initial set-up is shown in Fig. 1, wherein it is seen that the jaws 15 are horizontally aligned but non-parallel. The cycle of operation is performed, as described, although the different banks 20 perform to move the jaws from said non-parallel horizontal position to a position, after wrapping, with the jaws beneath and aligned with the opposite non-parallel sides of the die and 25 still horizontal although rotated through 90°, as before.

It will be realized that the different hydraulic components of the different banks thereof are controlled to exert force on and move jaws 15 in the desired compound path according to the 30 degree of taper of die 23.

The present machine can also handle taper-sectioned sheets of non-uniform width, as shown in Fig. 6. The pull on a taper-sectioned sheet 35 must vary as the cross-sectional area varies, in order to maintain a uniform stress in the sheet. Since stress is directly proportional to strain, it is only necessary to control the movement of each end of sheet-gripping jaws 15 to control 40 the stress in the sheet. This is done by using the control means 14 of the different banks to increase the tension on the successively thicker portions of the sheet until a desired sheet-elongating position has been reached by each end of the gripping jaws. Thereafter, the wrapping cycle is instituted, as before described. Thus, 45 from an initial flat pattern section that is tapered, the wrapped sheet is provided either with a lesser tapered cross-section or with a uniform cross-section, as desired.

Since the length of jaws 15 can be made to at 50 least equal the over-all dimension of the machine from front to back, two such machines may be installed side-by-side so as to handle sheets greater than twenty feet in length. In fact, the 55 number of banks may be varied as desired.

While it is conceivable that the above-described machine may have its various hydraulic components controlled by manual or like operation of valves admitting or releasing hydraulic 60 pressure thereinto, a more practical means for controlling the tensioning means 13, control means 14, and actuating means 17 is disclosed in Fig. 7, wherein the line 70 represents the center on which die 23 is positioned and the 65 mechanism shown on the right of said line is duplicated on the left thereof. In a three-bank machine as illustrated in Figs. 1, 2 and 3, the means shown in Fig. 7 would be applied to the two outer banks and, while also applied to the middle bank, the latter would also include the pressure-averaging means shown in Fig. 8.

Referring now more particularly to Figs. 7 and 9, hydraulic pressure fluid is admitted into 70 cylinder 26 of means 13 through a pipe 71 in

which the pressure from a suitable pump or other source, connected to pipe 72, is controlled by a pressure relief valve 73. An electric motor 74 is connected to valve 73 to adjust the relief pressure. A reversing motor is used, the same increasing or decreasing the pressure in pipe 71 according to the direction in which it is rotated. Said valve 73 exhausts through a pipe 75.

Pipe 71 is connected to cylinder 26 on the end thereof that will result in retraction of piston rod 28 when pressure fluid is admitted through said pipe.

Hydraulic pressure fluid is admitted into cylinder 37 of control means 14 through a pipe 76 in which a continuously operating pump 77 is employed to provide the pressure. Said pipe 76 is connected to cylinder 37 on the end thereof that will result in retraction of piston rod 40 and jaw 15 on the end of the latter.

An electric motor 78 operates to control the pressure-setting of pump 77. As said motor continues to operate, the pressure in pipe 76 increases. A fluid bleeder 79 is provided and normally is set to bleed the pressure in relation to the pressure in cylinder 26.

A suitable source of pressure fluid may be connected to cylinder 49 through a pipe 80 connected on the end of said cylinder that will result in a downward or retractive movement of stem 51.

Motor 74 is driven in one direction by an electric circuit 81 under control of a normally-open limit switch 82 and in the reverse direction by an electric circuit 83 under control of a normally-open limit switch 84. Both said limit switches are carried by rod 40. Switch 82 closes upon retractive movement of rod 40 by a cam actuator 85 mounted on cylinder 37, and switch 84 closes upon movement of cylinder 37 away from jaw 15 by a cam actuator 86 also mounted on said cylinder. The switches 82 and 84 may be carried by cylinder 37, in which case actuators 85 and 86 are mounted on rod 40.

To start motor 78, any suitable push-button control may be provided. Said motor 78 is also controlled by piston rod 28 as pressure in cylinder 26 is increased. A gear rack 87 carried by said rod 28 is engaged to rotate a pinion gear 88 mounted on a bracket 89 fixedly carried by cylinder 26. A grooved interrupter wheel 90 is rotated by gear 88 and intermittently controls a normally-open limit switch 91. An electric circuit 92 interconnects switch 91 and motor 78, and an impulse counter 93, set for a predetermined number of impulses created by the make-and-break action of switch 91, acts to open the circuit 92 and stop motor 78.

Said impulse counter 93, and such other electrical controls as may be employed in the machine, are advantageously grouped in a control console 94 physically remote from the machine but placed where an operator may control the operation of the latter.

Operation of controls

At the start of the initial stretching operation, motor 78 is set in operation to change the pressure setting of pump 77 to increase the pressure in cylinder 37 and retract rod 40. As rod 40 starts to retract from the first position of Fig. 9 to the second position, limit switch 82 is closed by actuator 85 to close circuit 81 to motor 74 and drive said motor in a direction to set relief valve 73 to increase pressure in cylinder 26. Thus, piston rod 28 starts to retract.

Retraction of rod 28 sets up rotation of interrupter wheel 90 to intermittently close normally-open limit switch 91 and, thereby, create a series of electrical impulses, through circuit 92, in impulse counter 93. When the predetermined number of impulses has been reached in said counter, the circuit to motor 78 is broken causing said motor to stop. The pressure in cylinder 37 will remain at the pressure setting of pump 77 which continues to operate.

During this time, the rod 28 is continuing to retract and the pressure in cylinder 26 is continuing to increase. When the force on rod 28 is greater than the force in cylinder 37, the latter cylinder will move in a direction away from the center of the machine as exemplified by line 70, because the fluid bleeder 79 will allow such movement of cylinder 37 relative to rod 40 and sheet 9. The pressure in cylinder 37 will be maintained, however, by pump 77.

When the cylinder 37 is thus moved, as shown in the third position of Fig. 9, actuator 85 moves with it to open limit switch 82, open circuit 81, and stop operation of motor 74. Whatever pressure the valve 73 has been set for during the mentioned operation of said motor is now maintained in cylinder 26. In this way, the sheet 9 is placed under stretching tension and the same is maintained preparatory to starting the sheet-wrapping operation.

The wrapping operation is accomplished by means 17. Pressure fluid is introduced through pipe 80 to retract rod 51 and, thereby, exert a downward pull on cylinder 37 through pivot 38. Since the pressure in control cylinder 37 is maintained constant by pump 77 according to pressure setting of said pump, there will be no additive force on rod 40 to create additional stretch force on sheet 9 as cylinder 37 is pulled by rod 51. In substantially the same way that bleeder 79 allowed cylinder 37 to move under pull of rod 28 without change in the set pressure in said cylinder, said bleeder now allows cylinder 37 to move under pull of rod 51, again without change of set pressure in said cylinder. As shown in the last position of Fig. 9, this movement of cylinder 37 closes limit switch 84 when cam actuator 86 is moved with said cylinder. Thus, the reverse circuit 83 for motor 74 is energized to reduce the pressure setting of relief valve 73. The pressure in cylinder 26 will, therefore, decrease.

It will be clear that as the rod 51 continues to exert its downward force, piston rod 28 projects or "pays out" by reason of said decreasing pressure in cylinder 26. It will be recalled that the cylinder 37 is being supplied with a constant set pressure. Consequently, as the pressure in cylinder 26 decreases rod 28 and cylinder 37 move back to the third position of Fig. 9, wherein switch 84 is open and the electric circuit 83 is broken to motor 74. At this point, the pressure in cylinder 26 stops decreasing and is maintained at the level to which the relief valve 73 had been reduced by the reversal of motor 74.

Since the successive positions of Fig. 9 are now passed in reverse order, switch 82 is then closed to restore the initial pressure in cylinder 26, and as piston rod 51 continues to move down, the foregoing sequence of operations repeats over and over again until the sheet is finally drawn to the wrapped position shown by the dot-dash lines of Fig. 2, or to any desired angular position short of a full 90° wrap.

The control function of means 14 will be readily apparent from the foregoing, the same acting to

increase and decrease the pressure in tension means 13 as the latter alternately pays out and maintains its pressure.

It will be realized that when the rod 51 of means 17 has reached its downward position, said rod will maintain a pulling force on sheet 9 that has been wrapped. Now, by using said means 17 to create an increased tension on the sheet, spring-back thereof is obviated.

Whether stretch-wrap forming over a die of uniform width or over a conical die, as shown in Fig. 1, the forces applied to means 13, 14 and 17 of the middle bank should be the average of the forces applied to the same means of the outer banks. This is necessary and desired so that jaws 15 are subject to uniform pull along their lengths although the pull at one end may be greater than that on the other end. In this way, the components of the three banks each pulls "its own weight." The means for this purpose is shown in Fig. 8.

In Fig. 8, the hydraulic units 100 are typical of the tension means 13, control means 14 and actuating means 17 of the two outer banks of the machine, and hydraulic unit 101 is typical of the same three means of the middle bank. Pipes 102 are typical of pipes 71, 76 and 80 of the two outer banks, and pipe 103 is typical of the same three pipes of the middle bank.

A pressure-dividing valve 104 is provided, the same comprising two cylinders 105 in tandem, each connected to one pipe 102 by a pipe 106, a piston 107 in each cylinder 105, and a single piston rod 108 connecting said pistons. The dividing valve 104 further includes a cylinder 109, an exhaust connection 110 between said cylinder and cylinders 105, a piston 111 in cylinder 109, and a piston rod 112 arranged parallel to piston rod 108. A lever 113 has a fulcrum 114 that divides the same into arms 115 and 116 that are engaged by the ends of rods 108 and 112. Arm 115 is half the length of arm 116. A pressure regulatable relief valve 117 is connected by a pipe 118 to pipe 103, and a pressure regulating pipe 119 extends from cylinder 111 to valve 117. The arrow 120 represents the force applied against lever arm 115 and arrow 121 the force transmitted by lever arm 116.

The pressure supplied through pipes 102 to chambers 122 of units 100 enters chambers 123 of cylinders 105 through pipes 106. Whether the same or different, these two pressures added together create the force 129 applied by rod 108 to lever arm 115. Since lever 113 has its arms at a one-to-two ratio, the force 121 transmitted by arm 116 to rod 112 is one-half the force 120. Although travelling twice the distance that rod 108 travels, rod 112 exerts a pressure in chamber 124 of cylinder 109 that is half the sum of the pressures in chambers 122 and, therefore, the average of said pressures.

The pressure in chamber 124 is added to the spring loading or setting of relief valve 117 through pipe 119. Since the relief valve, through pipe 118, controls the pressure delivered by pipe 103 to chamber 125 of cylinder 101, any increase in pilot pressure from chamber 124 will increase the pressure setting of said relief valve to increase the pressure in chamber 125. Any decrease of pilot pressure results in a decrease of pressure in said chamber 125. Therefore, the relief valve, according to pilot pressure from chamber 124, controls the pressure in unit 101.

While the invention that has been illustrated and described is now regarded as the preferred

embodiment, the construction is, of course, subject to modifications without departing from the spirit and scope of the invention. It is therefore not desired to restrict the invention to the particular form of construction illustrated and described, but to cover all modifications that may fall within the scope of the appended claims.

Having thus described the invention, what is claimed and desired to be secured by Letters Patent is:

1. A stretch-wrap forming machine comprising, in combination, a central support for a die over the surface of which a sheet is adapted to be formed, similar oppositely formed means on opposite sides of said support and die to stretch and wrap said sheet around said die, each said means comprising a first hydraulic cylinder unit having a piston rod directed toward said central support, a universally pivotal mount for said cylinder unit disposed laterally of said support and die, a second hydraulic cylinder unit pivotally carried on the end of said piston rod and having an extending piston rod, a jaw adapted to grip an edge of the sheet, a pivot connecting said jaw and the latter piston rod, said pivot being transverse to the pivot carrying the second hydraulic cylinder unit, a third hydraulic cylinder unit having an extending piston rod, a universal pivotal mount for the cylinder of the latter unit disposed on the side of the support that is opposite to the die therein, the piston rod of the third cylinder unit extending in a direction to intersect the piston rod of the first cylinder unit, and a universal connection between the piston rods of the first and third cylinder units.
2. A stretch-wrap forming machine comprising, in combination, a central support for a die over the surface of which a sheet is adapted to be formed, similar oppositely formed means on opposite sides of said support and die to stretch and wrap said sheet around said die, each said means comprising a first hydraulic cylinder unit having a piston rod directed toward said central support, a universally pivotal mount for said cylinder unit disposed laterally of said support and die, a second hydraulic cylinder unit pivotally carried on the end of said piston rod and having an extending piston rod, a jaw adapted to grip an edge of the sheet, a pivot connecting said jaw and the latter piston rod, said pivot being transverse to the pivot carrying the second hydraulic cylinder unit, a third hydraulic cylinder unit having an extending piston rod, a universal pivotal mount for the cylinder of the latter unit, and a universal connection between the piston rods of the first and third cylinder units, the third cylinder unit being disposed at an angle of approximately ninety degrees with respect to the disposition of the first cylinder unit.
3. A stretch-wrap forming machine according to claim 1: a guideway in which the universal pivotal mount of the third cylinder unit is movable, and means to adjust said mount in said guideway to position the same as desired relative to an edge of a die mounted on the central support.

4. A stretch-wrap forming machine according to claim 1: a guideway in which the universal pivotal mount of the third cylinder unit is movable, and means to adjust said mount in said guideway to position the same as desired relative to an edge of a die mounted on the central support, said latter means comprising a fourth hydraulic cylinder unit disposed laterally of the

latter mount and having a piston rod connected to said universal pivotal mount.

5. A stretch-wrap forming machine according to claim 1: means carried by the piston rod of the first cylinder unit and operatively connected to the pivot that carries the second cylinder unit to move said second unit on said pivot relative to the first cylinder unit.

6. A stretch-wrap forming machine comprising, in combination, a central support for a die over the surface of which a sheet is adapted to be formed, similar oppositely formed means on the opposite sides of said support and die to stretch and wrap said sheet around said die, each said means comprising a tension-imparting unit provided with a projectable and retractable member directed toward said support, a universally pivotal mount for said unit disposed laterally of said support and die, a tension-controlling unit pivotally carried by said projectable and retractable member and provided with a second projectable and retractable member, a jaw adapted to grip an edge of the sheet, a pivot connecting said jaw and said second projectable and retractable member, said pivot being transverse to the pivot carrying the tension-controlling unit, actuating means comprising a third projectable and retractable member, a universal pivotal mount for said actuating means disposed on the side of the support that is opposite to the die thereon, the third projectable and retractable member extending in a direction to intersect the projectable and retractable member of the tension-imparting unit, and a universal connection between the projectable and retractable members of the tension-imparting and actuating units.

7. A stretch-wrap forming machine according to claim 6: locating means connected to the universal pivotal mount of the actuating unit to adjust the position of the latter unit relative to an edge of a die on said central support.

8. A stretch-wrap forming machine according to claim 6: means carried by the first projectable and retractable member and operatively connected to the pivot of the tension-controlling unit to move the latter unit on said pivot relative to the tension-imparting unit.

9. A stretch-wrap forming machine according to claim 6: a plurality of tension-imparting, tension-controlling, and actuating units on each side of the central support and arranged in a plurality of parallel side-by-side banks, the jaw, on each side of the die support, extending in the direction of the longitudinal dimension of the support and in common pivotal connection with the second projectable and retractable members of the tension-controlling units of said plurality of banks.

10. A stretch-wrap forming machine comprising, in combination, a central support for a die over the surface of which a sheet is adapted to be formed, similar oppositely formed means on opposite sides of said support and die to stretch and wrap said sheet around said die, each said means comprising a tension-imparting unit having a

65

projectable and retractable member directed toward said central support, a fixed mount including a pivot for said unit for free pivotal movement of the unit in one plane relative to the die, a tension-controlling unit carried on a pivot on said member for pivotal movement of said tension-controlling unit in the same plane relative to said member, said tension-controlling unit also having a projectable and retractable member, a jaw adapted to grip an edge of the sheet, a pivot connecting said jaw and said projectable and retractable member of said tension-controlling unit for movement of said jaw in a plane transverse to the mentioned plane, and actuating means connected to the first projectable and retractable member to exert a pull on the pivot thereof to pivotally move the tension-imparting unit and the tension-controlling unit in said first-mentioned plane and to simultaneously move the jaw in a path around the die on the support and in the same first-mentioned plane.

11. A stretch-wrap forming machine according to claim 10: a plurality of tension-imparting, tension-controlling and actuating units on each side of the central support and arranged in a plurality of parallel side-by-side banks, the jaw on each side of the die support extending in the direction of the longitudinal dimension of the support and in common pivotal connection with the projectable and retractable members of the tension-controlling units of said plurality of banks.

12. A stretch-wrap forming machine according to claim 10: a plurality of tension-imparting, tension-controlling and actuating units on each side of the central support and arranged in a plurality of parallel side-by-side banks, the jaw on each side of the die support extending in the direction of the longitudinal dimension of the support and in common pivotal connection with the projectable and retractable members of the tension-controlling units of said plurality of banks, and a second pivot for the tension-imparting unit transverse to the pivot included in the mentioned mount of the tension-imparting unit and combining with the mount-included pivot to mount said tension-imparting unit to pivotally move in a plane transverse to the first-mentioned plane during angular movement of the jaw in its path around the die on the die support.
